UNITED STATES PATENT OFFICE

DANIEL RAYMOND MCNEAL, OF ABINGTON, PENNSYLVANIA, ASSIGNOR TO ANDALE ENGINEERING COMPANY, OF PHILADELPHIA, PENNSYLVANIA, A CORPORATION OF PENNSYLVANIA

HEATER OR COOLER

Application filed November 12, 1927. Serial No. 232,745.

This invention relates to heaters or coolers and particularly to casing and header construction of heating and cooling apparatus and the like.

5 Among the primary objects of the invention are to render a given heating or cooling unit readily adaptable to a variety of uses and to provide flexibility as to location of the device in the installation in which it is 10 employed.

The invention further contemplates the attainment of the foregoing in a simple and inexpensive manner.

Another object of the invention is to reduce 15 maintenance costs in connection with apparatus of this kind by making easier the inspection, cleaning, repair and replacement of parts.

Still another object is to provide, in a 20 heater or cooler having the foregoing advantages, improved means to prevent intermingling of the different fluids passing through the device, and to render obvious from the outside of the casing any leaks

25 which may develop at concealed joints.

How the foregoing, together with such other objects and advantages as are incident to the invention or will occur to those skilled in the art, are attained, will clearly appear 30 hereinafter, reference being had to the accompanying drawings, in which:

Fig. 1 is an elevational view of a heater or cooler showing my improvements in section; and

35 Fig. 2 is a section taken on the line 2—2 of Fig. 1.

The device comprises, in general, a casing 2, having a bottom closure 3 of ordinary construction which may have a convenient supporting base 4. At the top of the casing, and preferably bolted to a flange 5 thereof, is a tube plate or sheet 6 in which the ends of the two banks or groups of tubes 7, 8, are secured.

The bottom closure 3 forms a header or communicating passage from one bank of tubes

to the other at their lower ends, said lower ends being also secured in a suitable tube sheet (not shown).

The chamber formed by the casing 2 and the upper and lower tube plates has inlet and outlet openings 9, 10, for the heating or cooling fluid, as the case may be. Such fluid may be caused to take a sinuous or circuitous path among the tubes by any suitable means, such as baffles 11. Only one such baffle is here shown, but it will be understood that there are usually a number of them, spaced apart longitudinally of the chamber, of such width or diameter as to extend only partially across the chamber, and that they are placed alternately to one side and the other of the chamber. They may be made of a width slightly greater than half the diameter of the chamber, so that, when viewed in plan, their inner edges overlap (as shown in dotted lines in Fig. 2), to insure the proper sinuous travel of the heating or cooling fluid, i. e. to prevent short-circuiting of the fluid directly from end to end of the chamber.

At the top of the device is a two part head or header structure cooperating with the tube sheet 6 to form two passages or chambers 12, 13, the chamber 12 communicating with the tubes 8, and the chamber 13 with the tubes 7. This header structure comprises a flanged annular member 14, secured as by bolts 15 to the casing flange 5, and having inlet and outlet connections 16 and 17, and a cap or cover member 18, preferably secured to the ring 14 by bolts 19, and having an internal partition or dividing rib 20 which is adapted to cooperate with the tube sheet 6 by engagement with a groove 21 on said sheet. It will be seen that the fluid to be heated or cooled enters through inlet 16 and chamber 12 to tubes 8, passing down through said tubes and up through tubes 7 to chamber 13, and thence out through the connection 17.

The plate 6 or the flange 5, or both, may have an annular groove in line with the se-

curing studs or bolts 22, the groove 23, here shown, being located on the face of the flange 5. At the inner and outer sides of said groove are annular gaskets 24, 25. The joint 5 between the header member 14 and flange 5, and that between the member 14 and cover piece 18, are also provided, respectively, with gaskets 26 and 27. One of the bolt-holes 28 in the flange 5 is left open and provides a 10 vent to the atmosphere from groove 23.

From the foregoing it will be evident that by merely substituting different header members 14 having inlets and outlets 16 and 17 of different size or arrangement, the structure 15 is adapted to different uses, such substitution being impossible in the ordinary type of heater or cooler where the inlets and outlets are formed integral with the main casing of the device. Furthermore, by shifting 20 or turning the member 14 to bring different bolt holes in its flange in registry with the bolt holes in the flange 5 of the casing, the inlet and outlet connections may be shifted (as indicated in dot and dash lines in 25 Fig. 2) to suit various piping connections in different installations without the trouble of having to move the whole casing 2 and its base 4. In addition, by merely removing cover member 18, without disturbing the pipe 30 connections to inlet and outlet 16 and 17, the tubes may be readily inspected or the whole set of tubes may be lifted right out of the casing for cleaning or repair.

Along with such facility of repair and 35 flexibility of arrangement, the structure provides also for automatic disclosure of any leaks which may occur past the gaskets 24 and 25, when the fluids used are under pressure, by means of the groove 23 and the vent 40 28 to atmosphere. Likewise, any intermingling of the fluid in the tubes and their connecting passages with the fluid in the chamber of the main casing is positively prevented by virtue of the fact that leakage can only 45 take place to the outside, through said groove and vent.

In short, the simple combination of flanged casing, tube sheet, annular head member, and cover plate, as shown and described, accomplishes the objects and advantages desired. 50

What I claim is:—

1. In apparatus of the character described, a casing member and a tube plate member secured thereto, one of said members having a 55 groove cooperating with the other member to form a channel with a joint at each side thereof, a head secured to said casing member, said plate and casing forming a chamber and said plate, casing, and head forming another chamber, and an outlet connected to said channel.

2. In apparatus of the character described, a casing member and a tube plate member secured thereto, one of said members having a 60 groove cooperating with the other member

to form a channel with a joint at each side thereof, a head secured to said casing member, said plate and casing forming a chamber and said plate, casing, and head forming another chamber, and bolt-holes in said casing member communicating with said channel and also providing for insertion of plate-securing means. 70

3. In apparatus of the character described, a casing member and a tube plate member secured thereto, one of said members having a groove cooperating with the other member to form a channel with a joint at each side thereof, a head secured to said casing member, said plate and casing forming a chamber and said plate, casing, and head forming another chamber, and an outlet connected to said channel, together with fluid connections to said casing and fluid connections to said head. 75

4. In a heater or cooler, a main casing with a bundle of tubes therein, a tube plate having means securing it to the casing, a removable header member mounted on said casing adjacent said plate and having inlet and outlet connections, and a removable cover mounted on said header member said tube bundle and plate being removable from the casing upon removal of said cover without disturbing said header member or connections. 80

5. In a heater or cooler, a main casing with a bundle of tubes therein, a tube plate having means securing it to the casing, a removable header member mounted on said casing adjacent said plate and having inlet and outlet connections, and a removable cover mounted on said header member, said tube bundle and plate being removable from the casing upon removal of said cover without disturbing said header member or connections, and said header member with its connections being angularly shiftable without disturbing the tube plate securing means. 95

6. In a heater or cooler, a main casing open at one end and having a flange around said opening, a bundle of tubes in said casing having a tube plate with means for detachably securing it to said flange, and a header member carrying inlet and outlet connections with means for detachably securing it to said flange beyond the periphery of the tube plate. 100

7. In a heater or cooler, a main casing open at one end and having a flange around said opening, a bundle of tubes in said casing having a tube plate with means for detachably securing it to said flange, and a header member carrying inlet and outlet connections with means for detachably securing it to said flange beyond the periphery of the tube plate, together with a removable cover member for said header member detachably mounted thereon and being of greater diameter than said tube plate. 115

8. In a heater or cooler, a main casing open at one end and having a flange around said 120

- opening, a bundle of tubes in said casing having a tube plate with means for detachably securing it to said flange, and a header member carrying inlet and outlet connections with means for detachably securing it to said flange beyond the periphery of the tube plate, together with a removable cover member for said header member detachably mounted thereon and having internal rib means cooperating with said tube plate to form a plurality of chambers in said header member. 5
9. In a heater or cooler, a main casing open at one end and having a flange around said opening, a bundle of tubes in said casing having a tube plate with means for detachably securing it to said flange, and a header member carrying inlet and outlet connections with means for detachably securing it to said flange beyond the periphery of the tube plate, said plate having two annular seats on said flange, one on each side of the plate securing means. 10
10. In a heater or cooler, a main casing open at one end and having a flange around said opening, a bundle of tubes in said casing having a tube plate with means for detachably securing it to said flange, and a header member carrying inlet and outlet connections with means for detachably securing it to said flange beyond the periphery of the tube plate, said plate having two annular seats on said flange, one on each side of the plate securing means, together with an outlet connected to the space between said seats. 15
11. In a heat exchanger including a casing comprising a cylinder having an enlarged end constituting a chamber joined to said cylinder by a web, said chamber provided with an inlet and an outlet as well as with an open end, a plurality of tubes, a tube sheet for the tubes disposed in said chamber and secured to said web, as well as a detachable cover for said open end, the combination of packing between the tube sheet and said web; and a continuous groove in said web adjacent said packing to receive liquid seepage. 20
12. In a heat exchanger including a casing comprising a cylinder having an enlarged end constituting a chamber joined to said cylinder by a web, said chamber provided with an inlet and an outlet as well as with an open end, a plurality of tubes, a tube sheet for the tubes disposed in said chamber and secured to said web, as well as a detachable cover for said open end, the combination of packing between the tube sheet and said web; and a continuous vented groove in said web adjacent said packing to receive liquid seepage from said chamber and said casing and pass the same from said exchanger. 25
13. In a heat exchanger, the combination of a casing comprising a cylinder having an enlarged end constituting a chamber joined to said cylinder by a web, said chamber pro-
- vided with an open end as well as with an inlet and an outlet diametrically disposed in the side walls of said chamber, a plurality of tubes, a tube sheet for the tubes disposed in said chamber and secured to said web with packing therebetween, and a detachable cover for said open end provided with a central extension having formed surfaces exposed to said inlet and outlet. 30
- In testimony whereof I have hereunto signed my name. 70
